INVENTOR,
Henry N. Brawner, Jr.,
E. C. Braudeburg,
his ATTORNEY.

UNITED STATES PATENT OFFICE.

HENRY N. BRAWNER, JR., OF WASHINGTON, DISTRICT OF COLUMBIA.

DOOR-LATCH.

1,374,053.

Specification of Letters Patent.

Patented Apr. 5, 1921.

Application filed June 26, 1919. Serial No. 306,830.

To all whom it may concern:

Be it known that I, HENRY N. BRAWNER, Jr., a citizen of the United States, residing at Washington, in the District of Columbia, have invented certain new and useful Improvements in Door-Latches, of which the following is a specification.

My invention relates to an improvement in door latches, and more particularly such as are adapted for use on stallion stalls, where extraordinary strength is required to prevent the door of a box stall from being forced open by the animal confined therein.

This invention comprises among other features, a bar of metal constituting the latch, of considerable length, pivoted at one end to the door or gate at some distance from the edge thereof, with the free end thereof protruding some distance therebeyond, and passing through the vertical slot in a keeper rigidly secured to the edge of the door or gate, at right angles to the latch itself, in position to enter a catch secured on the door or gate post adjacent, also secured in a position at right angles to the latch, for securely fastening the door or gate, and at the pivoted end confined by a bridge plate which spans the latch and is itself secured to the door or gate, and a spring secured to the bridge plate by the same bolt which forms the pivot of the latch, thereby holding the end of the spring securely while the other end is so connected with the latch that it normally holds the latter in position to fasten the door or gate when closed and effectually prevent its being accidentally unfastened.

In the accompanying drawings,

Figure 1, is a view in front elevation showing my improved latch in operative position on a door.

Fig. 2, is a vertical section through the pivotal point of the latch,

Fig. 3, is a horizontal section taken through the same point,

Fig. 4, is a view of the guide, and

Fig. 5, is a view of the keeper.

A, represents the latch. This is preferably made of a long bar of metal which is adapted to lie flat against the door or gate to which my improved device is applied. The bridge plate 1, extends vertically over the inner or pivoted end and is secured at its ends to the door or gate 2, by screws or bolts 3, and a stiff spring 4, extends well out toward the free end of the latch with

its free end 5, bent inwardly and extending into a hole 6, formed in the latch to receive it, so that its downward tension is applied thereon well out toward the free end of the latch. The fixed end of the spring is extended inwardly around the inner vertical edge of the bridge plate 1, and it has a hole 7, therein, which registers with a hole 8, and a similar hole 9, in the bridge plate and the latch respectively and through these several holes 7, 8, and 9, a bolt 10, common to spring, bridge plate and latch, passes and is secured to the door or gate to hold all three parts in place and proper relation thereon, and against the possibility of being forced off by the animal confined within the stall no matter how much pressure he may happen to exert upon the door or gate from within.

The guide 11, is preferably in the form of a flat plate secured to the edge of the door or gate in any approved manner, that is, by means of screws or bolts 12, and at right angles to the latch and this guide is provided with a vertically disposed slot 13, of the desired length and just enough wider than the thickness of the latch to permit it to move freely therein, the inner edge of this slot being set flush with the surface of the door or gate as shown in Fig. 3, so that the latch is confined to a position close against the door or gate to which it is applied. The keeper 14, is also preferably made of a flat plate, with an open slot 15, at the upper, outer edge to receive the latch when the door or gate is closed, it being held by bolts or screws 16 to the door or gate post 17, parallel with the guide and at right angles to the latch, and its outer edge 18, is rounded or inclined to cause the latch to ride over into the slot 15.

Thus the guide, catch, bridge plate and spring all combine and coöperate to hold and confine the latch in place and by reason of the guide and catch being set as they are, that is, edgewise, and held by screws or bolts in positions at right angles to the latch so that the screws or bolts extend in a direction directly across any pressure that would be exerted upon the door or gate, it makes a strong and impregnable fastening.

The extreme end of the latch may be coiled around horizontally into the form of a loop 19, which serves as a handle and also as a means for fastening a rope or cable

20, which may be passed up over pulleys 21, and thence to some convenient place where an operator may pull it to release the door or gate, and several of them at the same time 5 from a common point without having to go to the door or gate to do it, a spring in that event being provided for each door or gate, to throw it open on being unlatched.

In this way I have provided a very strong 10 but simple latch which at the same time is easily made and applied and which effectually performs its functions.

I claim:

1. The combination with a guide and 15 catch, of a latch, a bridge plate, a spring, a stud passing through the opening in the latch, bridge-plate and spring, one end of said spring turned down against the bridge-plate to form a rigid connection therewith, 20 the free end of said spring received in an

opening in said latch to exert pressure upon the latch in one direction.

2. The combination with a door, a guide, and a catch, of a latch, a bridge plate arranged transversely of the latch, a stud supported by the door and adapted to pass through alined openings in the latch and bridge plate, and a spring adapted to extend parallel to the latch, one end thereof provided with an opening through which the 30 stud passes, the inner end of said spring bent downwardly against one end of the bridge plate for rigid connection therewith, the outer free end of said spring received in an opening in said latch to exert a downward 35 pressure thereupon to hold it in position, and means attached to the free end of the latch, whence the latch may be released.

In testimony whereof I affix my signature.

HENRY N. BRAWNER, JR.
